UNITED STATES PATENT OFFICE.

BENGT WIKTOR FJELLMAN, OF GOTENBORG, SWEDEN, ASSIGNOR TO AKTIEBOLAGET SVENSKA KULLAGERFABRIKEN, OF GOTENBORG, SWEDEN, A CORPORATION OF SWEDEN.

ROLLER-BEARING.

1,283,713.

Specification of Letters Patent.

Patented Nov. 5, 1918.

Application filed July 27, 1916. Serial No. 111,588.

To all whom it may concern:

Be it known that I, BENGT WIKTOR FJELLMAN, a subject of the King of Sweden, residing at Gottenborg, in the Kingdom of Sweden, have invented certain new and useful Improvements in Roller-Bearings, of which the following is a specification.

This invention relates to double row roller-bearings of the type having outwardly tapering conical rollers and having, between the two rows of rollers, a distance-ring or other spacing device adapted to keep the rollers in position relatively to the transverse central plane of the bearing and to take up the thrust from the race-rings which tends to move the rollers inward toward the transverse central plane of the bearing.

In bearings having cylindrical rollers, no such end thrust is exerted on them, and consequently the rollers are fairly easily guided and maintained in their correct position. In the case of conical bearings, however, there is considerable pressure exerted axially on the rollers and the friction may therefore become excessive; this is particularly so when the conical rollers are guided by gudgeon pins formed on each end engaging the spacing device and the object of this invention is to provide a conical bearing of the kind described, in which the friction is the least possible, without jeopardizing the retention and guidance of the rollers in exact positions relatively to each other.

The invention comprises therefore a double row of conical roller-bearing of the type described wherein the inner end of each roller is ground accurately plane at or in the proximity of its axis and each roller bears on an accurately ground part of the spacing device only at, or in the proximity of, its own axis. By forming the two sets of bearing-surfaces accurately smooth, and of the correct shape and size, it can be insured that each of the rollers has an accurate contact on the three sides, with the outer race-ring, the inner race-ring and the spacing device respectively with a minimum amount of friction.

The invention further consists in certain constructional forms of said arrangement, such forms being hereinafter particularly described.

In the drawings, several embodiments of the invention are illustrated, Figure 1 is a longitudinal section and Fig. 2 is a partial

end view of a roller bearing having a distance ring according to the invention. Fig. 3 is a section on line A—A of Fig. 1. Figs. 4 to 6 are longitudinal sections of parts of roller bearings having distance rings of different construction. Fig. 7 is a section on line VII—VII of Fig. 6. Fig. 7^a is a plan view of part of the roller cage shown in Fig. 6. Fig. 8 is a longitudinal section of a modified form of roller bearing, and Fig. 9 is a section on line B—B of Fig. 8. Fig. 10 is a longitudinal section, and Fig. 11 is a partial end view of a roller bearing in which balls are used for the distance ring. Figs. 12 to 19 show the invention applied to roller bearings having races of different forms.

Referring first to Figs. 1 to 3, the inner ring 1 is provided with a spherical race, while the outer ring 2 is provided with two conical races having their apices on the axis 75 of the bearing. Also the rollers 4 are conical in shape, the apices of the cones coinciding with the apices of the cones formed by the outer races. Placed between the two rows of rollers is a distance ring 5, on which 80 the rollers bear with their inner end surfaces which are plane next to the axes of the rollers, said ring serving to take up thrust from the rollers and to keep them at predetermined distances from one another and 85 from the radial center plane of the bearing, without too great friction arising at the contact points. The ring 5 is provided, at both sides, with wings or projections 6 designed to enter between the rollers of each set or 90 row and to keep the rollers of each set at predetermined distances from one another. The ring 5 thus also serves as an ordinary roller cage.

In the modification according to Fig. 4, 95 the ring 5 is provided with bolts 7 on which the rollers 4 are journaled. The bolts 7 belonging to one and the same set of rollers pass through a conical ring 8 bearing on the outer ends of the rollers; said ring may be 100 secured for instance by a wire 9 passed through the bolts or by the ends of the bolts being riveted so that the rollers and the ring 5 will form a single entity.

Fig. 5 shows a constructional form corresponding substantially to that of Fig. 4. The only difference is that, while the rollers of the two sets are placed in a staggered relationship in the form according to Fig. 4, 105 said rollers are placed right opposite each 110

other in the form according to Fig. 5. In the last mentioned form, a bolt 7 passing through the ring 5 and common to two oppositely arranged rollers can be used.

5 Fig. 6 shows a modification, in which the rollers are placed in a roller cage 10 made of sheet metal, said cage surrounding the distance ring 5. The two outer edges of said cage may be bent so as to form flanges 11 10 bearing on the outer end surfaces of the rollers, as shown at the righthand side of said figure.

In Fig. 7, a section through part of the roller cage, on line VII—VII of Fig. 6, is 15 shown.

Fig. 7^a is a plan view of a portion of the same roller cage.

Figs. 8 and 9 show a roller bearing, in which the side surfaces of the distance ring 20 5 are provided with circular projections 12 on which the inner ends of the rollers bear 25 at their centers. The ring 5 forms a roller cage by being provided with lateral projections 6 forming pockets for the rollers. Said pockets are formed so as to allow the 30 rollers to be inserted from within.

The distance ring may be replaced by 35 balls 13 placed in a roller cage 5, as shown in Fig. 10, the rollers bearing with the centers of their inner end surfaces on the balls. The balls may be placed for instance in 40 holes in the ring 5, as indicated at the top of Fig. 10, or in outwardly open pockets in said ring, in which latter case they may be kept 45 in position by an outer ring 14, as indicated at the bottom of Fig. 10.

In all the forms of embodiment hereinbefore described, the rollers bear along their 40 whole length on the conical races of the outer ring. This is, however, not essential, for 45 sufficiently good control of the rollers and sufficient bearing surface at the outer ring can be obtained when the outer races consist of two or more conical segments separated by recesses in the outer ring, as indicated by the dotted line 15 at the righthand side of the upper part of Fig. 1. Each race 50 can also consist of a single conical segment the width of which is smaller than the length of a roller. Such an arrangement is shown in Fig. 12.

Fig. 13 shows a modification in which the 55 races of the outer ring, viewed in cross section, are formed by circular arcs whose centers 16 lie at a certain distance outside the lines 17 which can be drawn through the center 18 of the inner spherical track and the centers of the rollers, so that the corresponding part of such race will act in the 60 same manner as the conical race hereinbefore described.

Fig. 14 shows a modification in which the 65 inner ring is provided with a separate convex race for each set of rollers.

All the roller bearings hereinbefore de-

scribed are self-aligning and provided with race rings each made in one piece. The mounting of such a bearing is performed in the following manner: The ring 5 is placed in the outer ring 2 and the rollers are filled 70 in, with the exception of two pairs of diametrically opposite rollers of the one set of rollers. The inner ring 1 is thereupon introduced into the space corresponding to the missing rollers, until it bears on the rollers 75 of the other set. The inner ring, which, while being inserted, has its axis perpendicular to the axis of the outer ring, is thereupon turned a quarter of a revolution about the axis of the outer ring so that the remaining 80 rollers can be placed in position. When this has been done, the inner ring is turned into the position in which its central plane coincides with that of the outer ring.

The invention can also be used in roller 85 bearings having divided race rings. Constructional forms of such bearings are shown in Figs. 15 to 19.

In the particular embodiment shown in Fig. 15, the outer ring and the inner ring 90 are provided with conical races having their apices on the axis of the bearing. The ring 5 is not shown to form a roller cage, but it is obvious that it may be arranged in such manner. The races of the outer ring are 95 formed of rings 21 and 22 separate from each other and from the outer ring 2, said rings being spherically formed on their outer sides and kept together by the outer ring which is spherical at its inner side. 100

In Fig. 16, the insertion of the previously built up bearing, consisting of the parts 1, 4, 5 and 21, and 22, into the outer ring 2 is illustrated. The outer ring 2 is provided, at one side, with two diametrically opposite 105 recesses 23 through which the rings 21, 22, with the rollers and the inner ring 1 placed therein, can be inserted at right angles to the plane of the ring 2, whereupon the rings 21, 22 can be turned into axial alignment with 110 the outer ring 2.

In Fig. 17, a roller bearing is shown in which the inner ring is provided with conical 115 races, while the races of the outer ring are formed in cross section along circular arcs the centers of which lie outside the lines 17 which can be drawn through the center 18 of the bearing and the centers of the rollers. The outer ring 2 is divided and kept together by a cylindrical ring 20 having bent 120 edges.

According to Fig. 18, the inner ring as well as the outer ring has conical races, the two parts of the divided outer ring being kept together by a cylindrical ring 20 having 125 bent edges.

In Fig. 19, a bearing is shown, the races of both rings of which, viewed in cross section, are formed along circular arcs. The radius of curvature of the cross section of 130

the races of the inner ring is greater than the radius of a sphere, touching the rollers at their inner sides. The outer ring is divided and kept together by a cylindrical 5 ring 20 having bent edges.

The bearings according to Figs. 17 to 19 are rigid, while the bearings having a spherically shaped inner race according to Figs. 1 to 13 are self-aligning.

10 In the above, different forms of the distance ring 5 have been described by way of example.

The projections 6 of the distance rings 5 formed as roller cages can be placed either 15 opposite each other (see for instance Fig. 8) or in staggered relationship (see for instance Fig. 1) according as it be desired that the rollers of the one set should lie opposite those of the other set, or not.

20 As to the rollers proper, they may be formed either with truncated conical end-surfaces as shown for instance in Fig. 1, or with curved (for instance spherical) end-surfaces, but in all cases the end surfaces of 25 the rollers themselves and the coöperating surfaces on the distance-piece, whether the

distance-piece itself or a ball carried by the distance-piece must be accurately ground to the correct size and finished.

I claim as my invention:—

30 1. A double row roller bearing having outwardly tapered conical rollers, the inner end of each roller being ground accurately plane at or in the proximity of its axis, a spacing device between the two rows of 35 rollers and having accurately ground faces for engaging said rollers and adapted to keep the same in position relatively to the radial center plane of the bearing to take the end thrust from the race rings, each 40 roller bearing on the spacing device at or in the proximity of its axis only.

2. A double row roller bearing having outwardly tapering conical rollers, the inner end of each roller being provided with a 45 frusto-conical end having an accurately ground plane face, and a spacing ring located between the rows of rollers and engaging each said roller at the said plane face.

In testimony whereof I affix my signature. 50

BENGT WIKTOR FJELLMAN.
